Primary Examiner — Patricia A Palasik

(57) **CLAIM**

The ornamental design for a mobile service robot loading box as shown and described.

DESCRIPTION

1. Mobile service robot loading box

1.1 : Perspective

1.2 : Front

1.3 : Back

1.4 : Left

1.5 : Right

1.6 : Top

1.7 : Bottom

The present design is mounted on a mobile service robot capable of transferring a product and providing various services to load and transfer various goods; reproduction 1.1 is a perspective view of a mobile service robot loading box showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof.

1 Claim, 7 Drawing Sheets
